UNITED STATES PATENT OFFICE.

JOHN KNIGHT, OF NEWARK, NEW JERSEY.

MACHINE FOR DRESSING MILLSTONES.

1,146,580.

Specification of Letters Patent. Patented July 13, 1915.

Application filed July 23, 1914. Serial No. 852,537.

To all whom it may concern:

Be it known that I, JOHN KNIGHT, a citizen of the United States, and a resident of the city of Newark, county of Essex, and 5 State of New Jersey, have invented a new and useful Improvement in Machines for Dressing Millstones, of which the following is a full, clear, and exact description.

My invention relates to improvements in 10 machines for dressing millstones, that is for cutting the grooves in the face of a stone.

My invention is especially designed for 15 dressing millstones such as are used in cocoa mills for grinding cocoa beans, but the invention can be used for dressing millstones for other purposes as will appear from the description which follows. In cocoa mills and analogous mills, the stones are arranged in series, the first having a deeper cut in its 20 face than those that follow, so that the grain or bean will be coarsely ground, and the following stones grind it successively finer. In grinding fibrous material of this kind the stones dull rapidly, and it has been the 25 usual practice, in cocoa mills at least, to dress the stones with a hand tool or chisel which is a slow process, and moreover the dressing cannot be done so accurately by hand as by machinery.

30 The object of my invention is to produce a portable dressing machine which can be set on the face of a stone, and the weight of which will hold it in place while it is being operated, and which by reason of its portability can be adjusted manually each time a new groove is to be cut. In carrying out this idea I provide a motor on the frame of the portable machine so that the whole apparatus is compact and can be adjusted together, and the motor will have the right 40 relation at all times to the cutting parts. Furthermore I provide two cutters adapted to cut the different depth grooves on the stone faces. In cutting the deeper grooves 45 which must have perfectly square edges in order to cut to the best advantage, I provide a rotary cutter which has preferably diamond points to do the cutting, and for the shallower grooves I provide a reciprocating chisel to do the cutting. Furthermore I arrange the cutters on a carriage 50 which can be adjusted forwardly as the groove is cut, which can be readily adjusted laterally so as to produce the right spacing 55 between the grooves, and also provide for adjusting the throw of the cutting chisel to

regulate the depth of a groove. The complete machine can be placed on the face of the millstone which is to be dressed, can be shifted to any desired position, and by 60 simply starting the motor the cutting can be commenced and accurately and rapidly carried out.

Reference is to be had to the accompanying drawings forming a part of this specification, in which similar reference characters indicate corresponding parts in all the views.

Figure 1 is a side elevation of the machine embodying my invention, the same being shown in position on a millstone. Fig. 70 2 is a broken plan view partly in section and with the rotary cutters removed, showing the machine on a millstone. Fig. 3 is a broken vertical section on the line 3—3 of Fig. 2, and Fig. 4 is a detail face view of the rotary 75 cutter.

The machine is provided with a flat base 10 which rests on the face of a stone to be dressed, and which is heavy enough to prevent the machine from tipping over. The 80 base constitutes a part of the frame, and at one edge it has a cross-bar 11 projecting on a line parallel with the base, and serving to carry a thin strip or plate 12 which serves as a track for the carriage truck as herein-after described. The plate 12 never carries 85 much weight and simply serves as a steady-ing means when the roller or truck 25 is not above the millstone, its chief function being to prevent the roller from running on the 90 face of the stone. Rising from the base and forming a part of the frame is a web 13 which at its upper and lower edges has inwardly extending flanges 14 in which longitudinal ways are made as shown by dotted 95 lines at 15, and in these ways runs the slide-plate 16 which supports the carriage, and by adjusting which the carriage is moved back-ward and forward. Projecting laterally from the plate 16 are bracket arms 17 which 100 are connected at the outer end by a plate 17^a (see Fig. 1) and these arms have a dovetail connection with the carriage 18 (see Fig. 3) so that the carriage may be moved laterally 105 on the said arms which serve as a track for the carriage.

The web 13 is recessed longitudinally on its inner side as shown at 19 in Fig. 1, and extending longitudinally through this re-cess is an adjusting screw 20, one end of 110 which is journaled in the plate 21 which is secured to the ends of the flanges 14, and

the screw is also connected with a fixed nut 22 in the way or recess 19, said nut being attached to the plate 16, and thus by turning the screw the plate 16 can be moved backward and forward. I have not shown this structure in detail, because it is a common means of adjusting similar parts in many kinds of machines. The screw 20 has at its front end a hand-wheel 23 by which it can be turned. To assist in supporting the carriage 18, and to also assist in preventing the machine from tipping, I provide a leg 24 on the outer end of the carriage, and this has a truck 25 at the bottom which runs on the track or plate 12 already referred to. This arrangement is shown clearly in Fig. 1.

The carriage is adjusted laterally by means of a screw 26 which is mounted on the plates 17^a and 16, and this screw connects with a fixed nut 27 on the back of the carriage, and has a hand wheel 28 at its outer end so that by turning the screw it will act on the nut 27 and slide the carriage 18 laterally on the arms or tracks 17. The roller or truck 25 is not pushed laterally of the track 12, because the carriage 18 is never moved far, as the machine as a whole is pushed around over the top of the millstone, and the carriage provides for nicer adjustment. On the inner side of the carriage is a vertically movable extension 29 which has a dovetail connection 30 with the carriage (see Fig. 2), and this extension can be adjusted vertically by means of the screw 31 which is journaled in a bracket 32 (see Fig. 3) on the under side of the carriage, and the screw connects with a fixed nut 33 on the back of the extension 29, so that by turning the screw the extension can be moved up and down. This is for the purpose of regulating the depth of the chisel cuts as will presently appear.

Attached to the extension 29 is a plate 34 which is bifurcated and which at the top 45 merges by means of the bracket arms 35 into a shelf 36 which carries the motor 36^a. This as shown is an electric motor, and is preferably of this type, but obviously the motor can be of any approved type, and it moves with the extension 29 so that it always has the same relation to the parts which it drives.

Covering the back of the plate 34 is a plate 37 which carries the bracket arm 38, and the parts 37, 34 and 29 are secured together by bolts 39 or equivalent fastenings. Sliding in the bifurcated part of the member 34 is the shank 40 of the cutting chisel 41. These parts are preferably separable, and can be connected in any usual or preferred manner. The shank 40 is normally pressed downward by a spring 42 which is arranged above it and the tension of which can be adjusted by means of the screw 43 which forms an abutment for the spring

and which extends through the top of the shelf 36. The shank 40 is raised against the tension of its spring by the following means: In the shank is a recess 44 which engages one end of the tripping arm 45, this being pivoted as shown at 46, and the outer end of the arm is struck and moved downward by the cam projections 47 which are carried by the shaft 48, so that as the shaft 48 revolves, the cams 47 will successively tilt 75 the tripping arm 45 and lift the inner end of the rod so as to raise the shank 40; but when the cam passes the outer end of the arm, the spring 42 will forcibly throw down the heavy shank 40 and chisel 41, thus making a cut in the face of the stone. Obviously the particular means of imparting movement to the shank 40 against its spring can be departed from without affecting the principle of the invention.

The shaft 48 is provided with tight and loose pulleys 49 and 50 connecting by a belt 51 with the driving shaft 52 of the motor 36^a.

The cutting mechanism above described is 90 for cutting the shallower grooves in a millstone, but for cutting the heavier grooves in the first stone of a series, which stone by-the-way, is exceedingly hard, a rotary cutter is necessary. To this end the extension 29 is 95 provided with bracket arms 53 (see Fig. 1) on the lower ends of which are bearing boxes 54 for the shaft 55 which carries the rotary cutter 56. The cutter is a thin disk having projections 57 thereon, and these carry the 100 diamond cutters 58 which are necessary to cut the very hard stone on which the cutter is used. By reference to Fig. 4 it will be noticed that these diamond cutting points are staggered, occurring alternately on opposite sides of successive teeth 57, so that a 105 groove is rapidly cut with perfectly straight edges.

When the machine is to be used, it is placed on the millstone 59, and the frame of 110 the machine can be moved to the desired point. The carriage 18 is then drawn out beyond the edge of the stone by means of the screw 20, and the motor is started. As the motor starts, the cutter 41 or 56 as desired, will be set in operation, and the carriage is fed across the face of the stone by means of the screw 20 above described. After a groove is cut, the carriage can be moved laterally by means of the screw 26, 120 which can be used at any time for nicer adjustment, or the frame can be moved as a whole for a general adjustment. It will be noted that the tool itself, if the cutting chisel 41 is used, can be made to cut deeper or less 125 deep by adjusting the extension 29 vertically in the manner already described. It will also be noted that the driving motor has always the same relation to the driven parts, that the whole machine can be moved around 130

on the face of the millstone as desired, and that the groove cutting can be regulated to a nicety by means of the adjusting mechanism shown and described.

5 Attention is called to the fact that the machine described can be used very rapidly and still do accurate work, and the rapid adjustment is to a large extent owing to the construction of the frame and the arrangement 10 of the adjusting and cutting parts thereon. By having a broad flat base which counter-balances the framework and which can be slipped in all directions, the operator slides the base and machine to the approximate 15 point of beginning operations, and then makes his finer adjustments by means of the carriage which carries the cutting mechanism. This is a great advantage as the machine as a whole can be easily moved about 20 to any desired point.

I claim:—

1. A machine of the kind described comprising a frame having a flat base serving to counter-balance the machine, and which can be moved freely on a millstone, a carriage 25 longitudinally and laterally adjustable on the frame, cutting mechanism, a vertical ex-

tension on the carriage carrying the cutting mechanism, a motor on the said extension, and an operative driving connection between 30 the motor and the cutting mechanism.

2. A machine of the kind described comprising a frame having a flat portable base of a weight to counter-balance the machine, a carriage longitudinally and laterally adjustable on the frame, a vertically adjustable extension on the carriage, and cutting mechanism carried by the said extension. 35

3. A machine of the kind described comprising a portable frame having a flat base, 40 a track connected with the base, a member rising from the base and having longitudinal ways thereon, a slide plate movable in the aforesaid ways, laterally extending arms on the slide plate forming a track, a carriage movable on the said arms, a truck connected to the carriage and running on the first mentioned track, and cutting mechanism 45 carried by the carriage.
